[57] CLAIM

The ornamental design for a baseball mitt, as shown and
described.

DESCRIPTION

FIG. 1 is a front elevational view of a baseball mitt
showing my new design;

FIG. 2 is a rear elevational view thereof;

FIG. 3 is a front perspective view thereof, the hand
shown in broken lines is for illustrative purposes only
and forms no part of the claimed design;

FIG. 4 is a side elevational view thereof, and,

FIG. 5 is a side elevational view thereof, of the opposite
side of FIG. 4.

FIG.1

FIG.2

FIG.3
